UNITED STATES PATENT OFFICE

128,158

DESIGN FOR A DISPENSER FOR TOOTH POWDER AND THE LIKE

Philip C. P. Booty, Chicago, Ill.

Application November 12, 1940, Serial No. 96,463

Term of patent 14 years

To all whom it may concern:

Be it known that I, Philip C. P. Booty, a subject of the King of Great Britain, residing at Chicago, in the county of Cook and State of Illinois, have invented a new, original, and ornamental Design for a Dispenser for Tooth Powder and the like, of which the following is a specification, reference being had to the accompanying drawing, forming part thereof.

In the drawing—

Fig. 1 is a side elevation of a dispenser for tooth powder and the like embodying my new design, the scoop thereof being in closed position;

Fig. 2 is an elevational view looking toward one end of the dispenser with the scoop thereof in closed position;

Fig. 3 is an elevational view looking toward the other end of the dispenser with the scoop thereof in closed position;

Fig. 4 is a plan view of the dispenser with the scoop thereof in closed position; and

Fig. 5 is a side elevational view of the dispenser with the scoop thereof in open position.

I claim:

The ornamental design for a dispenser for tooth powder and the like, substantially as shown.

PHILIP C. P. BOOTY.
